THE NORRIS PETERS CO., PHOTO-LITHO., WASHINGTON, D. C.

UNITED STATES PATENT OFFICE.

JOHN B. KELLY, OF PORTLAND, OREGON, ASSIGNOR OF ONE-HALF TO
CHARLES L. VAN BUSKIRK, OF LODI, CALIFORNIA.

MOTOR.

SPECIFICATION forming part of Letters Patent No. 651,862, dated June 19, 1900.

Application filed November 9, 1899. Serial No. 736,344. (No model.)

To all whom it may concern:

Be it known that I, JOHN B. KELLY, a citizen of the United States, residing at Portland, in the county of Multnomah and State of Oregon, have invented certain new and useful Improvements in Motors; and I do declare the following to be a full, clear, and exact description of the invention, such as will enable others skilled in the art to which it appertains to make and use the same.

The invention relates to motors.

One object of the invention is to provide a motor for any class of work, more particularly for feeding a sawmill-carriage to all kinds of sawmill-work, and to so combine the parts that the carriage in its travel will be contiguous to the piston in its movement from end to end of the cylinder, thus dispensing with the piston-rod now in use, which has its end connected to the carriage and which in order to drive the carriage the full length of the cylinder must be driven through the head of the cylinder the full length of the rod, which doubly increases the space required within which to operate the carriage.

A further object is to provide means for varying the stroke of the piston within the cylinder and correspondingly varying the length of the cylinder, so that the steam-space of the cylinder will not be greater in length than the travel of the piston.

A still further object is to provide a steam sawmill-feed which shall be simple of construction, efficient in operation, and comparatively inexpensive of production.

With these and other objects in view the invention consists in certain features of construction and combination of parts, which will be hereinafter fully described and claimed.

In the accompanying drawings, Figure 1 is a side elevation of my improved steam sawmill-feed, the ends of one of the carriage-rails and its sleeper being broken away. Fig. 2 is a longitudinal vertical sectional view looking toward that side of the machine shown in Fig. 1. Fig. 3 is a top plan view with the carriage removed. Fig. 4 is a vertical cross-sectional view on the line xx of Fig. 2 looking in the direction of the arrow. Fig. 5 is a vertical sectional view through the valve-chests. Fig. 6 is a detail perspective view of the pis-

ton-truck, showing in full lines the piston-arm broken off and in dotted lines the carriage-arm connected with the truck. Fig. 7 is a detail perspective view of the lower end 55 of the carriage-arm. Fig. 8 is a vertical sectional view of the movable-cylinder-head lock. Fig. 9 is a cross-sectional view on line yy of Fig. 8. Fig. 10 is a detail perspective view of one of the slide-valves. 60

Referring to the drawings, 1 denotes the ties of the track. 2 denotes the centrally-located piston truck-rail supported on said ties. 3 denotes longitudinal sleepers supported on said ties, and 4 denotes rails supported on 65 said sleepers.

5 denotes the part to be moved, shown in the present instance as a sawmill-carriage, which may be of any well-known or approved construction and which travels upon the 70 rails 4.

6 denotes an angular metallic supporting-beam, preferably in the form of the letter Z. 7 denotes a steam-cylinder bolted to the said beam and provided in its lower side with a 75 longitudinal slot 8, covered by a flexible band or ribbon 8', secured at its ends within said cylinder. 9 denotes a piston located within said cylinder and provided with an attaching-arm 10, which has an eye or transverse 80 aperture 11, through which the ribbon or band projects. This arm extends through the slot of the cylinder and is pivoted to a wheeled truck 12, which travels on the rail 2. An arm 13 is firmly bolted to the carriage and projects downwardly and thence laterally and is formed with prongs 14, which are adapted to pass through vertical apertures 15 in the truck and have a limited vertical movement therein, so as to compensate for any unevenness or 85 irregularities of the carriage-rails 4.

a b denote the end steam-chests, which communicate with the cylinder through ports a' b' , and c denotes the intermediate valve-chest, of which there may be as many as may 95 be desired and which communicates with the cylinder intermediate its ends through the port c' .

16 denotes an inlet-pipe having branches 17, which communicate with the inlet-ports 18 100 of the valve-chests. 18^a 18^b 18^c denote stop-cocks for said branch pipes 17. 19 denotes

an exhaust-pipe having branches 20, which communicate with the exhaust-ports 21 of the valve-chests. These branches 20 have stop-cocks 21^a 21^b 21^c. 22 denotes slide-valves 5 mounted in said valve-chests and connected together by a rod 23.

24 denotes a shifting-lever mounted in suitable bearings and pivoted to the valve-rod for shifting said valve within the chests to reverse 10 the movement of the piston within the cylinder. 25 denotes a movable cylinder-head which is mounted in one end of said cylinder and is provided with an attaching-arm 26, which is provided with a transverse aperture 15 or eye 27, through which the flexible strap or ribbon 8 passes. The lower end of the arm projects out through the slot in said cylinder and into a sliding block 28, the sides of which embrace the head of the rail 2 and is held in 20 place by a transverse pin 29, passing through apertures in the sides of said block and through apertures 30 in the rail.

31 denotes a suitably-mounted saw, shown in dotted lines, and 32 denotes the log, also 25 shown in dotted lines and supported by the carriage.

In operation, assuming that it be desired to saw a log of a length corresponding to that of the steam-cylinder, the intermediate valve-chest or valve-chests communicating with said cylinder are cut off from the inlet and exhaust pipes 16 and 19 by their respective cocks 18^b and 21^b. The cock 18^c is now opened to admit steam into the port 18 of the forward 30 valve-chest, and the cock 21^a is opened to exhaust steam through the branch 20 of the rearmost valve-chest. The shifting-lever is now actuated to shift the valves in said valve-chests to a position opposite to that shown in 35 Fig. 5 to admit steam into the forward end of the cylinder and to exhaust it from its rear end. The steam having thus been admitted to the forward end of the cylinder will drive the piston to the rear end, and consequently 40 move the saw-carriage, with its log, a corresponding distance past the rotary saw-blade, thus severing the log. To return the carriage, the shifting-lever is moved in an opposite direction to shift the valves to the position shown in Fig. 5, thus admitting steam to 45 the cylinder through the rearmost valve-chest and exhausting it from the cylinder through the foremost valve-chest. Assuming that it be desired to saw logs of a length considerably less than that of the cylinder, the rearmost valve-chest or valve-chests are cut off from communication with the inlet and outlet pipes by their cocks 18^a 21^a, and the 50 movable piston-head is slid up to a point immediately at the rear of the inlet-port *c'* of the cylinder and is locked in position to the rail 2 in the manner hereinbefore described. The cocks 18^b and 21^b are now opened to admit steam to the valve-chest, and the stroke of the piston 55 will correspond to the length of the steam-space within the cylinder, which length is the distance between the fixed head of the cylinder

and the movable head of the cylinder. By this arrangement only the amount of steam is consumed that is required to reciprocate 70 the piston the desired distance, while if the movable piston-head were not provided it would require the consumption of as much steam to reciprocate the piston a short distance in sawing short logs as it would to reciprocate it a long distance. This arrangement therefore effects a very material saving in running the machine and is one of the salient features of the present invention, the most important feature being the combining 80 of a sawmill-carriage with a piston in such manner that the carriage in its travel will be contiguous to the piston and will parallel the same throughout the entire movement of the piston. 85

While I have shown and described my invention as applied to sawmill-carriage, it is evident that the invention may be used for various other purposes, and for this reason I would have it distinctly understood that I do 90 not restrict myself to the use herein shown and described, but reserve to myself the right to employ the invention in connection with any machine or contrivance wherein a reciprocating movement is desired to be effected. 95

Having thus described the invention, what is claimed, and desired to be secured by Letters Patent, is—

1. The combination of a longitudinally-slotted cylinder, a movable head located within said cylinder, means for locking said head in its longitudinal adjustment within said cylinder, a series of valve-chests communicating with said cylinder and provided with inlet and outlet ports, valves arranged within 105 said chests, means for actuating said valves, a flexible band arranged within said cylinder to cover the slot therein, a piston traveling in said cylinder between the movable and stationary heads thereof, and an arm connected to said piston and projecting through the slot in said cylinder, substantially as and for the purpose set forth.

2. The combination of a longitudinally-slotted cylinder, a flexible band arranged 115 within said cylinder to cover the slot therein, a suitably-mounted wheel-truck, an arm connected to said piston and extending through the slot in said cylinder and connected to said truck, and an attaching-arm extending 120 from said truck, substantially as and for the purpose set forth.

3. The combination of a longitudinally-slotted cylinder, a flexible band arranged within said cylinder to cover the slot therein, 125 a suitably-mounted wheel-truck, an arm connected to said piston and extending through the slot in said cylinder and connected to said truck, a suitably-mounted carriage, and an arm extending from said carriage and connected to said truck so as to have a slight independent vertical and lateral movement relatively thereto, substantially as and for the purpose set forth.

4. The combination of a longitudinally-slotted cylinder, a flexible band arranged within said cylinder to cover the slot therein, a suitably-mounted wheel-truck, an arm connected to said piston and extending through the slot in said cylinder and connected to said truck, a suitably-mounted carriage, and an arm extending from said carriage and connected to said truck so as to have a slight independent vertical movement relatively

thereto, substantially as and for the purpose set forth.

In testimony whereof I have hereunto set my hand in presence of two subscribing witnesses.

JOHN B. KELLY.
